UNITED STATES PATENT OFFICE

2,361,902

WEARING APPAREL

Philip Sherman, Brookline, Mass.

Application March 9, 1944, Serial No. 525,632

3 Claims. (Cl. 2—237)

This invention relates to improvements in wearing apparel and more particularly to slacks, trousers, shorts, ladies' skirts and the like.

It is an object of the present invention to provide a practical, neat aesthetic-appearing and simple article of the aforementioned type which can be very readily and easily applied to and removed from the body of the wearer.

In articles of wearing apparel of the above-mentioned type it is a desirable feature that the garment be made such that it may be readily adapted to the body of the wearer, and where such articles are made with front drop flaps and side pockets, that the flap and adjacent parts be so constructed and designed as to withstand constant use and as not to interfere with the placing and withdrawal of the hands in and from the pockets, after the drop flap has been adjusted.

Furthermore, it is desirable that the pocket linings and portions of the apparel material around the pockets be so joined that when adjustment at the waist has been made, the pocket linings will not be exposed to view.

It is, therefore, another object of the present invention to provide an article of wearing apparel of the above-mentioned type which adapts itself to the waist line of the wearer, is sturdy around the movable parts, and wherein the front drop flap is so designed and constructed as to at all times permit easy access to the side pockets of the garment.

It is yet another object of the present invention to provide slacks, skirts or the like with the aforementioned construction which will maintain its attractiveness and style at any stage of waist line adjustment.

It is a further object of the present invention to provide a garment of the aforementioned type wherein the front drop flap is provided with a band portion cooperating in overlapping engagement with the band portion of the remainder of the article to constitute a complete waist encircling band which may be adjustable and wherein the overlapping parts of the waist band portions are each normally removably secured together at at least two points.

It is still another object of the present invention to provide slacks which may be readily and conveniently opened at its front top portion for permitting an easy dropping thereof for part or full removal of the garment and the replacing thereof.

Yet another object of the present invention is to incorporate the said desired features while

still maintaining the aesthetic and pleasing appearance of the garment.

Another object of the present invention is to provide slacks or the like, which does not require the use of separate belt means and which in themselves, are capable of being easily adjusted to the waist line of the wearer.

It is yet another object of the present invention to utilize a portion of the front drop flap as part of the pockets construction of the garment.

These and other objects and advantageous features are accomplished by the simple, novel and practical construction, combination and arrangement of parts hereinafter disclosed and illustrated in the accompanying drawing, constituting an essential part of the disclosure, and in which:

Fig. 1 is a front elevational view of the upper portion of the garment;

20 Fig. 2 is a rear view of Fig. 1;

Fig. 3 is a top plan view of Fig. 1 with the front drop flap being shown in lowered or downward position; and

Fig. 4 is a front view of the upper portion of the garment showing the front flap dropped.

25 Fig. 5 is a right-hand side elevational view of Fig. 1.

Referring now more particularly to the drawing, the invention is shown as applied to slacks 30 comprising leg-engaging section 12, waist-engaging section 13 and the mid-section 11.

Section 11 is provided with a loose front portion 15 constituting a drop flap terminating at its upper end in the waist band portion 13a having button-holes 16 adapted to accommodate the plurality of buttons 17 secured to waist band portion 13. It is preferable to provide the garment with a plurality of complementary fastening means such as two or more buttons 17 and button-holes 16 on either side of the vertical medial line of the flap 15, making the garment readily adjustable to accommodate the waist line size of the wearer and also to securely attach the flap to the waist band portion 13.

45 Flap 15 is seamed at 18 to side wall panels 19. The side wall panels 19 are each seamed at its upper edge to the end portions of waist band section 13 by the line of stitching 26. Secured to wall panel 19 by the line of stitching 25 and to

50 waist band section 13 by the continuation of the stitching 26, is one of the side walls 20 of pocket 22. This side wall 20 is preferably extended under panel 19 its entire area providing a lining therefor. The ends of waist band portion 13 extend respectively beyond side walls 20. Flap 15

has its side edges 15a particularly made arcuate as clearly seen in Fig. 1, these edges always overlying the panels 19 regardless of waist line adjustments made. Providing flap 15 with these arcuate or curved side edges permits easy access to the pockets 22 through opening 30 regardless of waist line adjustments made. Seamed to each of the side edges 15a of flap 15 by the line of stitching 15b and disposed on the underside of the flap is a marginal strip 23, the latter also being secured to waist band portion 13a between its layers 13b and 13c as by a line of stitching 31.

Secured to marginal strip 23, as by a line of stitching 32, and also to edge 15a by the line of stitching 15b, is the other side wall 21 of pocket 22; side wall 21 extending under marginal strip 23 constituting a lining therefor. This side wall 21 is secured at its upper end to waist band portion 13a between its layers 13b, 13c, as by the line of stitching 31.

The pocket side walls 20, 21 are joined together at their lower portions by the line of stitching 24 forming the cavity of the pocket for holding articles, this line of stitching terminating at 24a, leaving their upper edge portions 24b and 24c separate and the flap 15 free to be swung upwardly and downwardly.

The foregoing disclosure is to be regarded as descriptive and illustrative only, and not as restrictive or limitative of the invention, of which obviously an embodiment may be constructed including modifications without departing from the general scope herein indicated and denoted in the appended claims.

Having thus described my invention, what is claimed as new and desired to be secured by Letters Patent, is:

1. In an article of wearing apparel a back portion and a front portion, a waist band section secured to said back portion, said waist band section having spaced apart free ends extending to the front of said article, side wall panels secured to said back portion, said panels being spaced apart and being secured respectively at their upper ends to said waist band section, a lining for each of said panels, said lining being secured to said panel and to said waist band section and extending beyond said panel constituting a first side wall member for a pocket, said free ends of said waist band section extending beyond said panels and said linings, said front portion being secured to said back portion and to said panels at a distance below said waist band portions and being unsecured thereto thereabove providing a drop flap for said article, a waist band front section secured to said flap, said waist band front section adapted to overlie the free end portions of said first mentioned waist band section, a plurality of complementary fastening means on said waist band sections and on either side of the vertical medial line of said article, for maintaining said flap in upward position and adjusted relatively to said back portion, the sides of said flap being curved inwardly and overlapping said panels when said flap is in upward operative position, a marginal strip secured to each of said sides of said flap and being disposed therebehind, a second side wall member for each of said pockets, said second member being se-

cured to said strip and to said waist band front section, said first and second side wall members being marginally secured together at their lower portions constituting said pocket and having a portion of one of their adjacent side edges unconnected to permit the said flap to be swung upwardly and downwardly.

2. In an article of wearing apparel a back portion and a front portion, a waist band section secured to said back portion, said waist band section having spaced apart free ends at the front of said article, side wall panels secured to said back portions, said panels being spaced apart and being secured respectively at their upper edges to said waist band section, a first pocket forming side wall member at each of said panels, said member providing a lining for said panel and being secured to said waist band section and extending beyond said panel, said front portion being secured to said back portion at a distance below said waist band portion and being unsecured thereto thereabove providing a flap, a waist band front section secured to said flap and adapted to overlie the said free ends of said first mentioned waist band section, means on said waist band sections on either side of the vertical medial line of said article for removably attaching said flap to said first mentioned waist band section, the side edges of said flap overlapping said panels when said flap is in attached position, a second pocket forming side wall member secured to said waist band front section adjacent each end thereof, one of said second side wall members and one of said first side wall members being marginally secured together at their lower portions forming a pocket and having a portion of their side edges unconnected to permit the said flap to be swung upwardly and downwardly.

3. In an article of wearing apparel, a back portion and a front portion, a waist band section secured to said back portion, said waist band section having spaced apart free ends at the front of said article, side wall panels extending from said back portion, said panels being spaced apart and being secured respectively at their upper edges to said waist band section, a first pocket-forming side wall member extending laterally from each of said panels and being secured to said waist band portion, said front portion being secured to said back portion at a distance below said waist band portion and being unsecured thereto thereabove providing a flap, a waist band front section secured to said flap and adapted to overlie said free ends of said first mentioned waist band section, the lateral sides of said flap extending inwardly from its lower portion and upwardly and overlapping said panels when said flap is in an upward operative position, a second pocket forming side wall member secured to said waist band front section adjacent each end thereof, one of said second members and one of said first members being marginally secured together at their lower portions forming a pocket and having a portion of their side edges unconnected to permit said flap to be swung upwardly and downwardly and to provide an opening for said pocket when said flap is in said upward operative position.

PHILIP SHERMAN.
